UNITED STATES PATENT OFFICE.

WALTER CHMIELARSKI, OF GARY, INDIANA.

BOMB-DROPPER.

1,353,518.

Specification of Letters Patent. Patented Sept. 21, 1920.

Application filed April 17, 1918. Serial No. 229,023.

To all whom it may concern:

Be it known that I, WALTER CHMIELARSKI, a citizen of the United States, residing at Gary, county of Lake, and State of Indiana, have invented certain new and useful Improvements in Bomb-Droppers, of which the following is a specification.

This invention relates to improvements in apparatus for war purposes and particularly to those adapted to operate in the air, over the enemy.

The principal object of the invention is to provide a "heavier than air type" of flying machine with means whereby a bomb, which in itself is capable of operating in the air, may be released at any desired moment.

A further object is to provide a bomb having means within itself of traveling through the air after being released from the main machine, the flying bomb carrying a heavy explosive charge arranged to be detonated by concussion with any fixed object upon which it may drop.

These and other like objects are attained by the novel construction and combination of parts hereinafter described and shown in the accompanying drawing, forming a material part of this specification, and in which:—

30 Figure 1 is a side elevational view showing a conventional type of flying machine and indicating one of the bombs together with the manner in which it is operated.

Fig. 2 is a horizontal sectional view taken substantially on line 2—2 of Fig. 1.

Fig. 3 is a transverse sectional view taken on line 3—3 of Fig. 1.

Fig. 4 is an enlarged vertical sectional view taken through the flying bomb.

40 Fig. 5 is a further enlarged side view of the valve used in connection therewith.

Fig. 6 is an enlarged fragmentary sectional view taken on line 6—6 of Fig. 2, and

45 Fig. 7 is a transverse sectional view taken on line 7—7 of Fig. 6.

In Fig. 1 is shown the outlines of a flying machine 10, provided with planes 11, and having attached to its lower side, by vertical L shaped bars 12, longitudinally disposed 50 rails 15, the front sections 16 of which are supported by elements 18, pivoted upon spindles 19 to rigid bars 20, fixed on the machine so that the pivoted sections may separate and swing laterally outward from the 55 median line of the apparatus.

The extreme front ends of the rails 16

are joined with levers 22, journaled upon pins 23 in brackets 24 extending downward from the lower portion of the apparatus, the inner ends of the levers 22 being beveled on their lower sides as at 25.

These levers are supported upon a lug 28, formed with a lever 29 having an extending handle 30, reaching up through the lower wall or floor of the flying machine where it is readily accessible by the operator. The lever 29 is supported in a bracket 31 so as to be moved freely upon the pin 32. Coiled tension springs 35 are connected between the lower portion of the flying machine 10 and the longer horizontally disposed ends of the levers 22, so as to hold them normally in a raised position.

Engaged upon the rails 15 in such manner that they may slide, are the flying bombs, 75 prevented from rearward movement by the dogs 36, pivoted on pins 37 in the front and rear sections of the rails 15, the dogs being pressed upward into normal operative position by the compression springs 38.

The flying bomb is comprised of a casing 40 having a removable cover 41 and is supported by projecting lugs 42, the same normally resting and sliding upon the rails 15 and 16.

80 The rear section 44 of the casing contains a compartment 45 adapted to be filled with compressed air, which may be supplied from any convenient source through the plugged opening 46, while beyond the casing 44 extend the guiding vanes 47 and 48, respectively horizontal and vertical.

85 In the front compartment 50 formed by the casing 40 is a motor 51, adapted to be energized by compressed air supplied by reservoir 45, the compressed air entering through a pipe 52 set in the division or partition 53 which divides the reservoir from the engine compartment. The pipe 52 is controlled by a valve 55, the stem 56 of which has secured upon it a ratchet 57, and engageable with the ratchet teeth is a dog or pawl 58 normally pressed downward into contact by the spring 59, the pawl being carried by an operating lever 60, drawn normally forward by a coiled tension spring 61.

90 As shown in Fig. 4, the lever 60 is engaged by a plunger 62 having a limit or stop collar 63 secured upon it normally held against an inner abutment of the casing 40 by the spring 61 secured to said abutment and to lever 60, while the free end 64 of the

2
plunger extends through the casing. In this manner the valve 55 is normally held closed and during the forward movement of the bomb upon the rails 15 it can be opened by a pull on lever 60.

Operated by the motor 51 is a propeller 66 secured upon a shaft 67 entering into the compartment 50 and attached to the sides of the flying bomb are vanes or plates 68 whereby the bomb is measurably supported.

Engaged with the lower end of the bottom plate 70 formed with the casings 40 and 44 is an annulus 71, containing screw-threads with which is engaged the cone 72 adapted to contain and convey a charge of explosive 74 the same being detonated by a cap 75 when contact is made with the coned end of a plunger 76 projecting downward through the bushing or sleeve 77 and having at its end a head 78 adapted to make contact with any fixed object whereby the plunger is driven upward, causing the cap to be detonated and thereby setting off the powder charge 74.

In operation, the reservoir or tank compartment 45 having been filled with compressed air, under a high degree of compression, the bomb is moved along the rails 15 upon the sections 16 and when it is desired to liberate the same, the lever handle 30 is drawn rearwardly, permitting the rails to separate, due to the weight of the flying bomb, which is thus liberated. The lever 60 is then actuated by hand against the action of the spring 61 to open the valve which is shown in closed position in Fig. 4 and permitting the compressed air from the tank 45 to enter the motor, energizing the same and thereby actuating the propellers. During this movement of the lever 60 the pawl 58 will ride idly over the teeth of the ratchet secured to the valve. If then the lever 60 is released the valve will be actuated back to closed position by the spring 61 which in this case will draw the lever 60 back to the left. The operation of the propellers 66, if the flying machine is directed in the proper direction, will advance the flying bomb to a considerable distance in that direction. When the bomb

drops so that the plunger 78 comes in contact with a solid object, the charge is caused to be exploded in an obvious manner.

Having thus described my invention what I claim as new and desire to secure by Letters Patent, is.

1. In a bomb carrier, the combination with a flying machine of rigid bars secured to the machine, a pair of parallel spaced sectional rails extended from the lower side 60 of said flying machine, the front sections of said rails being hingedly engaged by said bars, means for normally holding said front sections of rails in alignment with the stationary sections, and for releasing said 65 hinged sections, bombs slideable on said rails, and a handle on said means for releasing said bombs at any desired interval.

2. In a bomb carrier, the combination with a flying machine, a pair of rigid parallel 70 rails extended below the frame of said flying machine, a pair of rails forming an extension of said rigid rails normally in alignment with said rigid rails, said second mentioned rails being pivotally supported, a 75 lever by which said rails are normally held in a raised position, a plurality of bombs carried upon said rails, said bombs being slidably mounted thereon, means for preventing rearward movement of the bombs, 80 and means for releasing said bombs from said pivoted rails.

3. In an aerial bomb carrying device, the combination with a flying machine having a pair of spaced rails extended rigidly therebelow, a pair of rails forming an extension of said rigid rails normally in alignment with said fixed rails, means for pivotally supporting said second mentioned rails 85 whereby they may move outwardly, a lever 90 adapted to hold said movable rails in a raised position, means for operating said lever from the interior of said flying machine, and a bomb fitted to slide upon said rails, said bomb being released by movement of said lever.

In testimony whereof I have affixed by signature.

WALTER CHMIELARSKI.
